UNITED STATES PATENT OFFICE.

ALBERT MOSBLACK, OF STEUBENVILLE, OHIO.

TITLE PRESS.

Application filed April 12, 1922. Serial No. 551,885.

To all whom it may concern:

Be it known that I, ALBERT MOSBLACK, a citizen of the United States, and a resident of Steubenville, in the county of Jefferson 5 and State of Ohio, have invented a new and Improved Tile Press, of which the following is a description:

The invention relates to a press having special utility in forming cement tile for 10 floors, walls, mantels, moulding, caps, sills, lintels, or other ornamental work in building structure although the invention is useful in operating on other material as for example for use by a baker in producing cakes 15 from materials of different colors or embodying various designs.

The general object of my invention is to provide a press of the indicated class having novel means for producing the article in 20 one, two, three or more colors at one operation.

The nature of the invention, its distinguishing features and advantages will clearly appear as the description proceeds.

Reference is to be had to the accompanying drawings forming a part of this specification, it being understood that the drawings are merely illustrative of one example of the invention.

Figure 1 is a plan view of a press embodying my invention;

Figure 2 is a vertical section as indicated by the line 2-2, Figure 1;

Figure 3 is a horizontal section as indicated by the line 3-3, Figure 2;

Figure 4 is an end elevation of a fragment of the machine, the lever being in vertical section;

Figure 5 is a vertical section of a tile produced in accordance with my invention.

In carrying out my invention in accordance with the illustrated example a suitable base 10 is provided from which rise posts 11 supporting a table top 12 on which the 45 articles are to be moulded. Rising from the base also are one, two, or more posts 13 flush with the surface of the table. Said table 12 has in practice a surface plate 12^a on which moulding is done.

50 A moulding frame is provided adapted to be imposed on the table 12 and here shown as consisting of side bars 14 through which elongated bolts 15 extend at opposite sides of the table, the said frame being completed by end bars 16 separate from the side bars 14 and rabbetted at their ends to be engaged

by a corresponding formation on the side bars.

The bars 14, 16 of the mould frame at their inner sides have vertical surface plates 60 17. The moulding frame is held in position by dowels 18 rising from the table 12 and accommodated in corresponding holes in the side bars 14. A clamp 19 is provided on the table at one side to bear against the outer 65 surface of one of the side bars 14, the opposite side bar lying adjacent to a thrust cleat 20 on the table 12.

The material to be moulded is placed in the frame 14 which may be rectangular to 70 produce a correspondingly shaped tile. In order to form a tile A or other moulded article with an insert or inserts a of different color, see Figure 5, the material to form the tile is placed within the bars 14, 16 and 75 spread over the surface of the table plate 12^a. The colored inserts are formed on the under side through the medium of auxiliary frames 21 here shown as in the form of rectangular tubes adapted to be projected 80 through the upper surface of the table 12 and its plate 12^a through slits 12^b in which the tubes 21 are adapted to have vertical guided movement. To raise or lower the tube or tubes 21 I provide a frame 22 rigid 85 therewith below the table top 12. A lever 23 is pivoted as at 24 to depending members 22^a on the frame 22, said lever being adapted to rock in a vertical plane for raising or lowering the frame 22 and with it the tubes 90 21. Said lever 23 is fulcrumed by extending it through an opening in a plate 25 (Figures 2 and 3) disposed vertically at a side of the fixed structure. Said plate 25 at the top and bottom of the opening therein forms 95 fulcrums for the lever 23 in raising and lowering the frame 22 and tube 21. In order to variously limit the throw of the lever 23 I provide a stop 26 in the form of a small flat plate disposed in a vertical plane and 100 secured to an element 27 secured to or forming part of the fixed structure, as for example, the two adjacent posts 11. The lower edge 28 of the stop 26 is of stepped form to variously limit the lever 23. The stop 26 105 may be a separate element held in position by the screw 29 and having a handle 30 for turning it about the fastener screw to present different portions of the edge 28 to the lever 23 for variously limiting the upward movement of the latter in the lowering 110 of the frame 22 and tubes 21.

With the above described arrangement a color or colors different from that of the body of the tile may be placed in the projecting ends of the tubes 21, said tubes being made to lie with their upper ends below the plane of the top of the moulding frame composed of the members 14, 16. Thus, the coloring material in the tubes 20, 21 will be covered by the material forming the body 10 of the tile and placed in the bars 14, 16 to a depth greater than that of the colored or contrasting surface. After the material is spread to fully occupy the upper ends of said tubes 21, said tubes may be lowered to 15 lie flush with the surface plate of the table and the material forming the body of the tile will then occupy the mold 14, 16 outside of the inserts. Obviously, with the tubes 21 lowered to the level of the surface 20 plate 12^a a tile or other article may be moulded of one material without colored or other contrasting inserts.

I would state in conclusion that while the illustrated example constitutes a practical 25 embodiment of my invention, I do not limit myself strictly to the exact details herein

illustrated, since, manifestly, the same can be considerably varied without departure from the spirit of the invention as defined in the appended claims.

Having thus described my invention, I claim:

1. A moulding means including a table, a moulding element movable vertically to project above said table, a frame carrying said element, a vertically rockable lever connected with said frame, and an adjustable stop movable to different positions and adapted to variously limit the movement of said lever.

2. In a moulding machine of the class described, a plurality of posts, a table on said posts, movable hollow elements projectable through said table, a lower frame mounting said hollow elements, a lever pivoted adjacent the center of said lower frame, a plate acting as a fulcrum for said lever secured to said posts, and means on one of said posts for controlling the movement of said lever whereby to project said hollow members a predetermined distance.

ALBERT MOSBLACK.
